COMPASS CARD REFINISHING STAND

Maurice Kidjel, Honolulu, Territory of Hawaii

Application October 12, 1945, Serial No. 622,104

8 Claims. (Cl. 101—126)

(Granted under the act of March 3, 1883, as
amended April 30, 1928; 370 O. G. 757)

1

The invention described herein may be manufactured and used by or for the Government for governmental purposes without payment to me of any royalty thereon.

This invention relates to a device primarily intended for reconditioning and refinishing compass cards but may be equally effective in stenciling new cards of this type.

An object of the invention is to provide means for correctly stenciling the calibrations of the compass cards in proper alignment with their magnets.

Another object is to provide means to stencil fine, exact and uniform figures and degree marks on the cards.

Another object is to provide means for restoring bent or otherwise distorted cards to their original shape.

Other objects and advantages will be evident from a consideration of the following description taken in conjunction with the drawings, wherein:

Fig. 1 is a top plan view of the assembled device.

Fig. 2 is a vertical section taken at 2—2 of Fig. 1, showing the stencil in place but with the work removed for clearness.

Fig. 2a is a bottom plan view of the stencil holder head and the stencil retainer as these two parts appear when assembled together but removed from the remainder of the stencil holder assembly.

Fig. 2b is a vertical axial section through the stencil holder head taken on the line 2b—2b of Fig. 2a but with the stencil retainer removed.

Fig. 3 is a view of the fully assembled device taken at 3—3 of Fig. 1.

Fig. 4 is a top plan view of a compass card assembly showing the outside of the frusto-conical card and the top of the float.

Fig. 4a is a bottom plan view of the compass card assembly showing the inside of the frusto-conical card, the bottom of the float and the magnets.

Fig. 4b is an axial section taken at 4b—4b of Fig. 4a.

Fig. 5 is a view of the arcuate thin sheet metal stencil, the openings of which are accurately machined on an engraving machine, the arcuate shape being adapted to take frusto-conical form when the ends are brought together.

Like reference characters refer to like parts throughout the several views.

Referring more particularly to Fig. 1 of the drawings, a base 10 is provided at one end with an upwardly extending post 12 threaded into the

2

base at the lower end as at 14 and having the upper end reduced to a smaller diameter as at 16. A cavity 17 in the end of the base is for a purpose which will hereinafter appear. At the other end, a stem 18 is threaded into the base 10 as at 20, the upper portion of the stem being reduced in diameter as at 22. A concentric opening extends through the portion 22 and part way through the larger portion of the stem 18 for the purpose of slidably receiving an ejector 24. A transverse opening is provided in the stem 18 for the ejector operating plunger 26 which is yieldably held in the position shown by a spring 28. A washer 30 secured to the left hand end of the plunger 26 by a screw 32 limits the amount that the spring 28 may move the plunger 26 to the right. A portion of the plunger 26 at 34 is so tapered that movement of the plunger 26 against the resistance of the spring 28 raises the ejector 24. The purpose of the ejector is to remove the work if, for any reason, it sticks in the fixture.

A compass card adapter assembly 35 consists of an adapter body 36 which, at its lower end, has a hub 38 having an opening that is slidably freely over the tubular portion 22 of the stem 18 but may be fastened in place on said tubular portion by the thumbscrew 40 (see Fig. 3). The upper cup-shaped portion of the adapter body is externally beveled as at 42 to fit the interior of the frusto-conical compass card 44 of the compass card assembly 45 (see Fig. 4b). Fastened in the cupped upper side of the adapter body 36 by screws 46 is a relatively thin-walled collar 48, the interior of which is adapted to receive the float portion 50 of the compass card assembly 45. Transverse notches 52 are formed in the collar 48 to receive the magnets 54 which are carried on the bottom of the float 50 (see Fig. 4a). At the upper end the two pairs of notches 52 are each pair joined into one wide notch 55. Additional narrower notches 56 are provided in the collar 48 ninety degrees around from the wide notches 55 to clear the ears 58 which join the compass card to the float. Notches 55 and 56 have the additional function, which will be hereinafter described, of cooperating with a member on the stencil holder for aligning the compass card assembly with the stencil. A shield 60 rests upon a shoulder on the adapter body 36 to keep the paint spray off the working parts 18, 26, 28, etc.

With the adapter and its associated parts, above enumerated, assembled as shown, the compass card assembly 45 may be positioned in the

the stem 12. The bushing 84 may preferably be press-fitted into the arm 86.

The arm 86 is split at 88 and provided with a thumbscrew 90 and a bolt 92 whereby the arm may be fixed in any position to which it may be swung. A spring 94 placed between the top of the nut 80 and the bottom of the bushing 84 urges the stencil assembly downward to provide proper pressure between the stencil and the work. A washer 96 is held to the end of the spindle 14 by a screw 98 to limit downward travel of the stencil assembly 62. The operation of the device is substantially as follows:

It may be assumed that the stencil 68, Fig. 5, has been placed in the recess 70 of the stencil head 64 with the joint of the stencil centrally located under one of the bridges 71 which brings all of the bridges exactly midway between two of the degree marks (see Fig. 3) and twelve and one-half degrees anticlockwise (viewed from the top) from the N, E, S and W positions and that the stencil head 64 has also been turned in relation to the stencil retainer 78 until the center line through the bridges 71 is also twelve and one-half degrees off the center line of the lugs 79 and 81 but is coincident with the other center line which passes through the N, E, S and W positions of the stencil.

In order to insert a compass card assembly 45 the thumbscrew 90 should be loosened, the arm 86 raised and swung to one side, and a compass card assembly 45, Figs. 4, 4a and 4b placed with the frusto-conical card 44 on the outside and the float 50 on the inside of the adapter assembly 35 and with the magnets 54 lying in the grooves 52.

The arm 86 may now be returned to position and lowered so that the stencil head assembly 62 fits down over the adapter assembly 35 with the compass card assembly 45 between, and with the lugs 79 and 81 of the stencil retainer 78 entered into the notches 55 and 56 of the thin-walled collar 48. After the stencil assembly 62 engages the compass card assembly 45, the arm may be brought down somewhat farther to slightly compress the spring 94 and thereby raise the washer 96 from contact with the top of the bushing 84 whereby the work may always be held under a uniform pressure and any distorted cards be returned to their original shape.

The card may now be sprayed through the windows 67 and when sufficiently dry may be removed from the fixture by again loosening the thumbscrew 90, raising the stencil holder assembly off the work and swinging the arm 86 to one side. The ejector plunger 26 may then be pushed inward to raise the compass card assembly 45 off the adapter assembly 35. When retouching or any other handwork is to be done, the thumbscrew 40 may be loosened and the adapter 35 with the compass card assembly 45 thereon laid in the cavity 17 as seen in Fig. 2, whereby handwork may be conveniently performed.

Having described an embodiment of my invention, I claim:

1. For renewing the degree marks and the N-S and E-W positions on frusto-conical compass cards of the type having a float concentrically supported within the card with open space between, and a pair of bar magnets carried on the bottom of the float, a fixture which comprises a base, a stem extending upwardly from said base, an adapter assembly concentrically supported on said stem, said adapter assembly being formed on the outside to fit into said compass

fixture, the float 50 lying within the collar 48, and the beveled inside of the frusto-conical compass card 44 fitting over the beveled upper side 42 of the adapter body 36. The upper edge of the collar 48 which is not cut away by the notches 55 and 56 will reach upward through the arcuate openings 57 between the compass card 44 and the float 50, being thereby positioned to cooperate with the stencil holder to align the compass card with the stencil. Thus assembled the compass card assembly 45 is ready to have the stencil applied thereto.

The stencil holder assembly 62 consists of a head 64 the under side of which is first bored at 66 to the same taper as the compass card 44 but to a greater depth and to a diameter which will allow the lower edge of the head 64 to come about flush with the lower edge of the compass card 44 when the parts are assembled as in Fig. 2. To provide space in the head 64 for the stencil 68 (see Fig. 5) the tapered bore 66 is further provided with a shallow recess 70 which extends from a point near the top of the bore 66 to a point near its lower edge (see Fig. 2b).

When so made, the recess 70 will receive the stencil 68, Fig. 5, when the ends are brought together to produce a stencil of frusto-conical form. In order to expose the outer surface of the stencil 68 when it is in place in the holder 64, four windows 67 are cut through the side walls of the holder, see Figs. 2a and 2b, leaving only a ring 69 supported on the body of the holder by the narrow bridges 71. The hub 72 on the upper side of the stencil head 64 has an opening for the spindle 14 to the lower threaded end 76 of which a stencil retainer 78 is secured. Stencil retainer 78 is so cut away at its periphery as to leave lugs 79 and 81 which are of a size and spacing to fit into the end of the notches 55 and 56 respectively of the thin-walled collar 48 which fixes the relation of the magnets to the N position.

From Fig. 2a it may be seen that the lugs 79 and 81 of the stencil retainer 78 with respect to the bridges 71 are turned 12½° anticlockwise, and an inspection of Fig. 5 will show that the center line of the arcuate sheet metal stencil 68, which will assume a frusto-conical form when inserted in the recess 70 of the stencil head 64, is also turned 12½° anticlockwise off the N line. It follows that when the stencil head assembly 62, with the stencil 68 in place, is brought down over the compass card adapter assembly 35, with the compass card assembly 45 in place, the joint in the stencil 68 will be under one of the bridges 71, and the N position in the stencil will be 12½° off the center of another of the bridges 71, whereby neither the N position nor any other of the openings in the stencil are inaccessible for spraying. It also follows that the magnets 54 will be parallel to the center line passing through N and S. A nut 80 on another threaded part 82 of the spindle 14 draws the stencil retainer 78 into the smaller tapered opening thereby holding the stencil 68 in its recess 70.

In order to facilitate description, the stencil holder 64 has been described by the process of making it out of a piece of solid steel. It will be obvious, however, that this and other pieces of the device may be die cast or otherwise fabricated, the procedure selected being governed by the number of the devices to be made. The upper end of the spindle 14 is slideable in a bushing 84 which is supported in the arm 86 which is in turn swingable on the upper reduced end 16 of

card and on the inside to receive said float, and having locating grooves for the magnets and a locating portion with circumferentially spaced notches extending upwardly from said adapter through said open space, said notches corresponding to the N-S and E-W positions on the card, a spindle coaxially positioned above said stem, a stencil holder assembly concentrically positioned on said spindle, said stencil holder assembly comprising a stencil head having its interior shaped to hold a frusto-conical stencil which is adapted to fit over said compass card, said stencil head having a series of windows for access to the outer surface of said stencil, with bridges between the windows of less thickness than the space between any two of the degree marks on the stencil, and a stencil retainer in said stencil head adapted to clamp said stencil by its upper edge, said retainer having circumferentially spaced lugs for engagement with said circumferentially spaced notches, said lugs being rotatably offset a whole number of degree marks plus half of a degree mark with respect to said bridges and in alignment with the N-S and E-W axes of said stencil.

2. The device of claim 1 wherein the stencil consists of an arcuate strip of thin sheet metal adapted to have its ends brought together to form the frustum of a cone, and with the degree marks and the N-S and E-W positions cut therethrough, the joint where the ends of the strip come together being offset from the S position a whole number of degree marks plus half of a degree mark.

3. For renewing the degree marks and the N-S and E-W positions on frusto-conical compass cards of the type having a float concentrically supported within the card with open space between and a bar magnet carried by the float, a fixture which comprises a base, a stem extending upwardly from said base, an adapter concentrically supported on said stem, said adapter being formed on the outside to fit into said compass card and on the inside to receive said float, and having a locating groove for the magnet and a locating portion extending upwardly from said adapter through said open space, a spindle coaxially positioned above said stem, a stencil holder concentrically positioned on said spindle, said stencil holder comprising a stencil head having its interior shaped to hold a frusto-conical stencil which is adapted to fit over said compass card, said stencil head having a series of windows for access to the outer surface of said stencil with bridges between the windows of less thickness than the space between two of the degree marks on the stencil, and a stencil retainer in said stencil head adapted to clamp said stencil by its upper edge, said retainer having locating means for engagement with said locating portion, said locating means being rotatably offset a whole number of degree marks plus half of a degree mark with respect to said bridges and in register with one of the N, S, E or W positions on said stencil.

4. The device of claim 3 wherein the stencil consists of an arcuate strip of thin sheet material adapted to have the ends brought together to form the frustum of a cone, and with the degree marks and the N-S and the E-W positions cut therethrough, the joint where the ends of the strip come together being offset from one of the N, S, E or W positions a whole number of degree marks plus half of a degree mark.

5. For stenciling the degree marks and the N-S

and E-W positions on frusto-conical compass cards of the type having a bar magnet suspended therefrom for rotation therewith, a fixture which comprises a base, an adapter assembly supported on said base, said adapter assembly being formed to a frusto-conical shape to fit into said compass card and having a locating pocket for receiving the magnet, and a stencil locating portion extending upwardly from said adapter above said compass card, a stencil holder concentrically positioned with respect to said adapter, said stencil holder comprising a stencil head having its interior shaped to hold a frusto-conical stencil which is adapted to fit over said compass card, said stencil head having a series of windows for access to the outer surface of said stencil with bridges between the windows of less thickness than the space between two of the degree marks on the stencil, and a stencil retainer in said stencil head adapted to clamp said stencil in said stencil head, said retainer having locating means for engagement with said locating portions, said locating means being rotatably offset a whole number of degree marks plus half of a degree mark with respect to said bridges but in register with the N-S and E-W positions on the stencil.

6. The device of claim 5 wherein the stencil is composed of an arcuate strip wherein a center line bisecting the strip passes midway between two degree marks, whereby the joint formed where the ends come together is positioned under one of the bridges.

7. For stenciling the degree marks and the N-S and E-W positions on compass cards of the type having a bar magnet attached thereto, a fixture which includes an adapter formed to receive and support said compass card, said adapter having a locating pocket for the magnet and a stencil locating portion extending therefrom, a stencil holder having its interior shaped to hold a stencil which is adapted to fit over said compass card, said stencil holder having a series of windows for access to the outer surface of said stencil with bridges between the windows of less thickness than the space between two of the degree marks on the stencil, and a stencil retainer in said stencil holder adapted to clamp said stencil in said holder, said retainer having locating means for engagement with said locating portion, said locating means being rotatably offset a whole number of degree marks plus half of a degree mark with respect to said bridges and in register with one of the N, S, E or W positions on said stencil.

8. A fixture for stenciling the degree marks and the N, S, E and W positions on compass cards of the type having a magnet carried by the card, said fixture comprising an adapter having means to support a card and having magnet locating pockets and stencil locating means formed therein, a coaxial stencil holding means having cooperating stencil locating means so set with respect to the stencil as to bring the N-S line in the stencil in alignment with the magnet when the cooperating stencil locating means is engaged with said stencil locating means.
